CLAIM

The ornamental design for a stringed instrument plectrum, as shown and described.

DESCRIPTION

FIG. 1—is a top plan view of a stringed instrument plectrum showing my new design, the undisclosed bottom view being a mirror image thereof;

FIG. 2—is a side elevational view thereof, the undisclosed opposite side being mirror image; and,

FIG. 3—is a top end view of FIG. 1.

1 Claim, 1 Drawing Sheet

FIG. 1

FIG. 2

FIG. 3
